(Cl. D61—1)

To all whom it may concern:

Be it known that we, John H. Eagle and Kenneth A. Van Dyck, citizens of the United States, residing at Rochester, in the county of Monroe and State of New York, have invented a new, original, and ornamental Design for a Photographic Enlarger, of which the following is a specification, reference being had to the accompanying drawings, forming a part thereof, in which:

Fig. 1 is a top plan view of a photographic enlarger, and;

Fig. 2 is a perspective view of the same, showing our new design.

We claim:

The ornamental design for a photographic enlarger, as shown.

JOHN H. EAGLE.

KENNETH A. VAN DYCK.
